UNITED STATES PATENT OFFICE

FERDINAND VON MADALER, OF HAMPTON BAYS, NEW YORK, ASSIGNOR, BY MESNE ASSIGNMENTS, TO VISIONOLA MFG. CORPORATION, OF NEW YORK, N. Y., A CORPORATION OF DELAWARE

SOUND RECORDING MECHANISM

Application filed March 1, 1926. Serial No. 91,483.

This invention relates to improvements in sound recording mechanism, and to a mechanism of this character more particularly adapted for use in recording sounds directly 5 on standard motion picture strips in a cold state during the movement of the film strip through the mechanism.

An object of this invention is to provide a mechanism adapted to efficiently record 10 sound on a standard motion picture celluloid film strip in a cold state during the movement of the film strip through the mechanism, and which utilizes the small space between the 15 opening for the sprocket teeth and the edge of the picture surface of the film for the sound record groove.

Another object of the invention is to provide a mechanism for recording the sound on a standard motion picture film strip in 20 the cold state in which in the movement of the film through the mechanism the recording needle is operated in a uniform manner by the sound vibrations to be recorded in the strip and provided with suitable 25 controlling mechanism to force the needle into the strip during the recording operation and prevent the same from scratching the film and being vibrated for recording undesirable vibrations of the mechanical structure 30 of the recording mechanism.

The invention further comprehends the efficient recording of sound on a standard motion picture film strip in a cold state by impressing the sound record in the strip with 35 the provision of suitable means for producing a uniform operation of the strip under the sound recording needle by providing mechanism to rigidly hold and guide the film strip in a predetermined manner under 40 said recording needle.

This invention further provides for the construction of a recording mechanism adapted to uniformly feed a film strip therethrough, preferably a standard motion picture film strip for receiving a sound record from the recording mechanism forming part of the device which is especially constructed and adapted for operation with sound amplifying mechanism and sound recording mechanisms of any desired type, preferably

electrically operated mechanism by means of which the sound transmitted is efficiently recorded in the film strip without appreciable mechanical noise or the recordation of undesirable sounds.

The invention comprehends numerous other objects resulting from the details of construction and operation of the parts in the production of efficient and clear sound records on the motion picture strip which are more particularly pointed out in the following detailed description and claims, directed to the preferred construction of the invention, it being understood however, that various changes may be made in the construction and relation of the parts without departing from the spirit and scope of the invention as herein set forth.

In the drawings forming part of this application:

Figure 1 is a side elevation of one side of the improved recording mechanism with parts in operative position.

Fig. 2 is a side elevation of the opposite side of the recording mechanism from that shown in Fig. 1.

Fig. 3 is an enlarged vertical sectional view taken on the line 3-3 of Fig. 1, illustrating particularly the manner of mounting and operating the recording stylus in carrying out this invention.

Fig. 4 is a vertical sectional view taken approximately on the line 4-4 of Fig. 3, and particularly illustrating the recording stylus structure and mounting in side elevation.

Fig. 5 is a detail view of the section of film with a sound record thereon.

A pair of supporting standards forming part of the base structure of the mechanism are indicated at 1 which extend upwardly in spaced parallel relation and support the entire mechanism in operative relation. A main drive shaft 2 is rotatably mounted in the standards 1 and provided with a shoulder at 3 having bearing contact with the inside face of one of the standards 1 as shown in Fig. 3 and against which it is held through the medium of thrust plate 4 engaging the reduced end 5 of the shaft having bearing contact therein in order to prevent end play

of the shaft and consequent lateral motion of the film passing over the sprocket roller construction indicated generally, by the numeral 6. This sprocket drive roller 6 for the 5 film includes a pair of cooperating end sections 7 and 8 respectively which are formed with sprocket teeth 9 adapted to engage in the opening of the film 10 and drive the same during the rotation of the shaft 2.

10 A hardened steel disk 11 is assembled between the drive roll sections 7 and 8, the entire assembly forming the drive roll being held in assembled relation by suitable screw threaded rods 12. The purpose of the hardened steel disk will be presently pointed out.

15 The standards 1 are provided with upwardly extending detachable arms as indicated at 13 from one side thereof in the upper end of which is pivotally supported a

20 roller carrying plate 14 which is recessed throughout the central portion of one edge to provide a pair of arms, and which receive the idling roller structure formed by a pair of cooperating roller sections 16 and 17 re-

25 spectively independently and rotatably mounted on the shaft section 18 in a predetermined spaced relation. The roller sections 16 and 17 are of hollow construction as shown to provide an internal chamber indicated at 19 while shoulders 20 formed on the shaft 18 determine the position of the roller sections against which they are held to prevent endwise movement. For this purpose suitable thrust washers 21 are positioned

30 between the ends of the roller sections and the arms of the plate 14. The shaft 18 extends through openings formed in the ends of the arms of said plate and is held in position by suitable set screws 22. An upright

35 projection 23 mounted on the plate adjacent the pivoted end thereof carries a horizontal arm 24 adjustably mounting the weight 25 normally applying a downward pressure on the plate 14 to move the same about its pivot 40 and hold the roller sections 16 and 17 firm 45 down in engagement with the film for holding the same in a true and flat relation on the surface of the drive roller structure 6.

One end of the shaft 18 is provided with 50 a bore 26 and at the inner end of the bore an opening extends radially through the shaft at 27 for a purpose which will presently appear. Each of these roller sections 16 and 17 are provided with annular grooves 28 55 adapted to receive the sprocket teeth on the drive roller assembly 6 in the operation of the device, while the section 17 is of reduced diameter at 29 to receive the annular flange 30 on the roller assembly 6 extending from 60 the peripheral edge of the section 8 of said roller assembly.

The carrier plate 14 is provided with depending hangers 31 in which one end of the recorder supporting member 32 is pivotally 65 mounted as indicated at 32'. This recorder

supporting member is of substantially narrow cross section adjacent the periphery of the roller sections 16 and 17 and extends through the slot formed by the spacing of said section. Within the chamber 19 formed 70 in the roller section the recorder support carries a cylindrical weight 33 which is formed integral therewith, while a web projection from the support at 34 extends outwardly through the slot between the roller sections 16 and 17 and carries a guide pin 75 35 slidably engaging in the bifurcated end of the guide plate 36 mounted on the supporting arm 37 secured to one of the standards 1. This provides a mounting for the recorder 80 which will prevent lateral movement thereof as well as vibration which would cause oscillation of the recorder member and the recordation of undesirable sound in the sound record being recorded on the film strip. 85

The supporter recording member 32 is formed with an enlarged central opening 38 which receives the shaft 18 and within the chamber 19 the said member is formed on one side thereof with a pair of spaced projections 39 arranged in a substantially and normally horizontal plane forming bearings supports for the recorder carrying member 40 having the spaced pin bearing 41 so that the recorder carrying member is mounted for free oscillating movement on said bearing projections 39. The recording member 40 has a downwardly extending portion 42 which carries the recorder or stylus 43 and in connection with this invention the stylus carries a diamond point 44 the end portion of which is formed substantially round as well as of conoidal shape. A supporting spring 45 of curved construction has a threaded end receiving the nut 46 adapted to engage the projection 47 on the recorder supporting member 32 so that the tension applied to the recorder carrying member 40 may be adjusted to a desired degree to produce a uniform and efficient sound record groove in a film 90 strip without distortion or the recordation of mechanical sounds resulting from the operation of the recording apparatus. 100

The recorder carrying member 40 is provided with an upwardly extending arm 48 115 projecting through the opening 27 in the shaft 18 and provided with a laterally extending end portion 49 projecting outwardly beyond the supporting members 1 through the bore 26 in said shaft for connection with a suitable vibratory diaphragm (not shown) of a sound operated device of any suitable character known to the art and used in conjunction with the recording of sound on a strip or disk record. The operating rod 48 120 for the recorder member together with the lateral extension 49 is formed of substantially resilient material so as to permit of an axial movement of the portion 49 without necessitating a pivotal connection between the rod 125 130

and the recorder member, but at the same time efficiently transmitting sound vibrations applied thereto for the purpose of oscillating the recorder member on the pin bearings 41 and thereby producing an oscillation of the diamond point 44 to impress a wavering groove in the celluloid film strip 10 in which the sound record is being made and wherein the sound record will be produced 10 by the horizontal undulation in the groove formed by the diamond point in said film strip.

As the character of the celluloid film strip in which the sound record is made by this invention is of substantially tough and varying intensity and as it is sometimes of a rather sticky nature, it has been found necessary to provide means to prevent the vibration of the recorder carrying member 32 and consequently the impression of waves in the record not produced by the sound, but by the oscillation of the plate caused by the unevenness and stickiness of the material of the film strip. For this purpose a pair of pins extend from opposite sides of the projection 34 of the plate 32 as indicated at 51 over which is engaged the bifurcated hook pin of a head 52 to the lower end of which is pivotally connected a lever 53 pivotally mounted in the supporting arm 37 by means of the transverse pin 53' and having a substantially long arm 54 carrying the adjustable weight 55 thereon. This lever structure 53 with the weight 55 has a substantially different period of vibration 5 than that of the recorder mounting member 32 and in being engaged with the pin 51 on the free end portion of said plate 32, the vibration tendencies of the recorder plate will be transmitted to the lever 53 and in view of 0 the different period of vibration of said lever, the vibrations of the recorder member 32 will be absorbed by the lever. In this way, the recorder member will be prevented from vibrating in response to the variations in consistency of the film strip and practice has shown that the recording needle or stylus will be moved over the film strip for forming a sound record groove and recording sound in said groove in a uniform even manner and thereby produce a clear and undistorted record of the sounds applied thereto.

A suitable guide for the film is illustrated at 56 for guiding said film onto the guide sprocket rolls 6 from the reel housing 57 while suitable idler rollers 58 and 59 serve to guide the film as it leaves the recording mechanism and to retain the same on the periphery of the drive roll for a sufficient distance to maintain the sprocket teeth in driving engagement with the film. The film is wound in any suitable manner on a suitable reel contained within the housing 60.

An L-shaped arm 61 is attached to one edge of the plate 14 as shown in Fig. 2 and extends forwardly and downwardly and terminates

in close proximity to the upper end of one side of one of the standards 1. The lower end of the L-shaped arm 61 carries a manually operable hand lever 62 having a cam hook 63 thereon which is adapted for engagement with the upper end of the standard 1 so that in the position shown in dotted lines in Fig. 2, the cam will operate the arm 61 and move the carrier plate 14 on its pivot to raise the roller structure. The other elements carried by said arm include the recording stylus carried above the drive roller assembly 6 and the film thereon so that the film may be fed into the machine in a convenient manner and also to prevent the recorder from engaging 75 and forming the sound groove in the film.

In the operation of this recording mechanism, a standard moving picture film is used as shown in Fig. 5 which includes a series of picture squares 65 positioned in the central portion throughout the length of the film 66 while the edge portion is formed with the usual series of openings 67 for receiving the sprocket teeth for the driving sprocket for the film. The picture squares 65 are always substantially larger than the actual projected portion of the picture in view of the fact that the opening in the film gate is always smaller in size than the size of the picture squares. In addition, there is a slight space 90 between the edges of the picture squares and the edge portion of the film provided with the openings 67 which does not come in contact with the mechanism for driving and retaining the film in passing through a motion picture projector, and which face is used by the present invention for receiving the sound record on the celluloid side of the film which is the back side, so that it will not be projected through the opening in the film gate 95 in the projection of the pictures and also will be free of engagement with the driving apparatus for the film. In this way a sound record can be placed on a standard motion picture film which will not be affected or 100 damaged in the use of the film. The sound groove is indicated in Fig. 5 by the numeral 68. The film is fed from the reel within the housing 57 through the film guide 56 and between the guide roll 6 and the idler roller sections 16 and 17 respectively in the manner as illustrated in Fig. 4.

The film is held in contact with the surface of the drive roll 6 until it passes under the idler 58. The film then extends over the idler 120 roller 59 and is drawn into the casing 60 for winding on a suitable reel.

After the film is fed through the recording device as just described, during which time the lever 62 is in the full line position of Fig. 2, the lever 62 is then operated to permit the roller sections 16 and 17 to be lowered into engagement with the film as indicated at 10 in Fig. 3 which will also permit the recording point 44 to engage the film in a free man-

ner for recording sound waves therein. The weight of the roller sections 16 and 17 in addition to the weight of the carrier plate 14 and the force applied thereto through the weight 25 on the arm 24 will serve to force the film down into intimate contact with the face of the drive roll 6 and maintain the same in such relation around the point of engagement of the recorder point 44 with the film. In this way the film will be held perfectly flat and passed through the recording mechanisms and under the point of the recorder in an accurate and uniform manner for receiving the record of the sound waves during the operation of the recorder member thereby.

The driver roller 6 as well as the roll sections 16 and 17 in assembled relation are of such construction that the faces thereof engaging the film are of a width slightly less than that of the film so that in the passage of said film between the said rollers, one edge portion thereof will project beyond the ends of each of the roller structures. A bracket 25 69 is mounted on one of the standards 1 as shown in Figs. 2 and 3, which is provided with a recess 70 slidably receiving the plunger 71 having the disk thereon indicated at 72 which is projected by the spring 73 outwardly from the bracket and toward the ends of the rollers 6 and 16 for engagement with the edge of the moving picture film in order to hold the same against lateral motion between the rollers and in engagement with the flange 30 30 of the drive roll 6.

By the construction of the recorder mechanism as above described, it should be clearly understood that the rolls 16 and 17 as well as the sprocket roller 6 are held against end movement in the standard 1 as well as relative to each other by the provision of suitable structural elements to prevent end play in the structure. It will also be clear that the film in being passed between the rolls 45 is held in a flat manner and also prevented from moving laterally relative to the faces of the rollers in order that the sound record may be impressed and formed in the moving picture strip in a most efficient manner and 50 without the recording of mechanical or other undesirable vibrations.

The construction of the recording mechanism is of such a character that the point of engagement of the diamond point 44 with the motion picture film will be in the same transverse alignment with the point of engagement of the roller sections 16 and 17 with the film and the point at which the film is held in intimate contact with the surface of the drive roll 6, so that it may not warp, twist, or have any lateral movement under the recording stylus. The construction therefore, guides the film at the point of engagement of the recorder therewith in a predetermined man-

ner so that an efficient and clear sound record may be made in the film.

As pointed out above, a hardened steel disk 11 is mounted between the drive roll sections 6 and 8 and the peripheral surface thereof 70 coincides with the surface of the roll section 7. It will be noted that in Fig. 3 the hardened steel disk is in alignment with the recording stylus, thus providing a very regular and hardened surface beneath the film during the recording operation. The roll sections 7 and 8 are necessarily made of soft material to permit the cutting of the sprocket teeth therein but this material may be subject to warping and twisting such as would interfere with proper recording of sound. Certainly if the roll sections, 6, 7 and 8 were hardened after the teeth were cut there would be such warping and shrinkage of the sections 80 and sprocket teeth as to interfere with the proper running of the film through the recorder. The arrangement provided by applicant with the hardened steel disk 11 overcomes these difficulties.

The particular construction of this mechanism will eliminate the noises caused by vibration of the mechanical parts of the device and it has been found from actual experience, that a very clear sound record is produced in 90 the film.

Having thus described my invention, what I claim as new is:—

1. A mechanism for recording sound on a strip, comprising, in combination, a support for the strip having a supporting surface adapted to travel with the strip throughout a predetermined zone, and adapted for engagement by a recording mechanism operable to engage said strip within said predetermined zone, and means cooperating with said support for guiding the strip in a predetermined path, including a guide yieldably engaging one edge of the strip for retaining the same in intimate contact with the support in the zone of engagement of said recording mechanism therewith.

2. A mechanism for recording sound on a strip, comprising, in combination, a rotatable support, a record strip adapted for movement over said support and in engagement therewith throughout a predetermined zone in sound recording position with a sound recording mechanism having a needle, adapted for engagement with said strip, and rotatable means for cooperation with said rotatable support adapted to engage the film in the zone of engagement with said support, and to retain said film in intimate bearing contact with said support adjacent the point of engagement of the recording needle with said strip and including a rigid guide carried by said rotatable support forming an abutment for one edge of the strip and a yieldable guide engageable with the opposite edge thereof 130

- whereby to urge the strip against said rigid guide.
3. A mechanism for recording sound on a strip, a cylindrical supporting member for the strip mounted for rotative movement, with the strip arranged on a portion of the surface thereof in traveling movement thereover, whereby to support the strip in sound recording position having a recording mechanism having a recording needle operable to engage said film strip at the point of engagement thereof with said support, and means substantially encircling said recording mechanism for engagement with said strip adapted to retain the same in engagement with said support and said recording mechanism.
4. A mechanism for recording sound on a strip, a cylindrical supporting member for the strip mounted for rotative movement, with the strip arranged on a portion of the surface thereof in traveling movement thereover, whereby to support the strip in sound recording position with a recording mechanism having a recording needle operable to engage said film strip at the point of engagement of said strip with said support, and means encircling said recording mechanism for engagement with said strip adapted to retain the same in predetermined relation with said support and said recording mechanism, and cooperating means adapted to guide said film strip on said support in its movement thereover for retaining said strip in engagement with said support.
5. A mechanism for recording sound on a strip, comprising a support for the strip permitting movement of the strip over said support, whereby to arrange the strip in sound recording position with a recording mechanism having a recording needle adapted for engagement with said strip on said support, and gravity actuated means attached to said recording mechanism operable to substantially eliminate and absorb mechanical vibrations impressed on said recording mechanism and prevent the recordation thereof on said strip.
6. A mechanism for recording sound on a strip comprising a support for the strip permitting movement of the strip over said support, whereby to arrange the strip in sound recording position with a recording mechanism having a recording needle adapted for engagement with said strip on said support, means attached to said recording mechanism operable to eliminate and absorb mechanical vibrations impressed on said recording mechanism and prevent the recordation thereof on said strip, and means encircling said recording mechanism for maintaining said strip in uniform engagement with said support in the zone of said recording needle.
7. In a mounting for a sound recording

mechanism for strip material comprising a support having means for feeding and guiding the material to receive a sound impression, a recording mechanism supporting member pivotally mounted on said support, means carried thereby for attaching the recording mechanism for oscillatory movement thereof transversely to the path of travel of the strip and means for retaining the supporting member against transverse movement.

8. In a mounting for sound recording mechanism for strip material comprising a support having means for feeding and guiding the material to receive the sound impressions, a recording mechanism supporting member pivotally mounted on said support, means carried thereby for attaching the recording mechanism for oscillatory movement thereof transversely to the path of travel of the strip, means for retaining the supporting member against transverse movement and means arranged at the free end of said member yieldably permitting vertical movement thereof.

9. In a mounting for a sound recording mechanism for strip material comprising a support having means for feeding and guiding the material to receive the sound impressions, a recording mechanism supporting member pivotally mounted on said support, means carried thereby for attaching the recording mechanism for oscillatory movement thereof transversely to the path of travel of the strip, guide means engaging the free end of said member preventing transverse movement thereof and an adjustable weight carried by said free end of the member yieldably restraining the same against upward movement.

10. Mechanism for impressing a sound record in celluloid or like substance comprising, in combination, a support for the celluloid record, a recording member adapted to be actuated from a sound vibrated member, means for moving the celluloid record and recording member relatively, and means for preventing mechanical vibrations other than the sound vibrations from affecting the sound record to an extent that will impair the sound record.

11. Mechanism for impressing a sound record in celluloid comprising, in combination, a support for the celluloid record, a recording member adapted to be actuated from a sound vibratory member, means for moving the celluloid record and recording member relatively, and means for automatically compensating for variations in the consistency of uniformity of the celluloid record.

12. Mechanism for impressing a sound record in celluloid comprising, in combination, a support for the celluloid record, a recording member adapted to be actuated from a sound vibratory member, means for moving the cel-

luloid record and recording member relatively, a support for the recording member permitting movement thereof transverse to the path of relative movement between record and recording member, and a resilient connection between the sound vibrated member and the recording member.

13. A mechanism for recording sound on strips of material, said mechanism comprising a support, means carried thereby for feeding and guiding a strip of material, a recording mechanism, a member pivotally mounted on said support and carrying the recording mechanism, the recording mechanism being mounted to oscillate in a direction transversely to the path of travel of the strip, and sound vibrated means for actuating the recording mechanism.

10 In testimony whereof I affix my signature.
